UNITED STATES PATENT OFFICE.

HERBERT P. SCHMECK, OF PHILADELPHIA, PENNSYLVANIA, ASSIGNOR TO PHILADELPHIA TOBOGGAN COMPANY, OF PHILADELPHIA, PENNSYLVANIA, A CORPORATION OF PENNSYLVANIA.

GRAVITY-OPERATED COASTER.

Application filed December 20, 1926. Serial No. 155,974.

My invention relates to amusement systems, and it has particular relation to gravity-operated coaster apparatus.

One object of my invention is to provide a coaster, wherein the friction of the flanged wheels while traversing a curved track section is reduced to a minimum value.

Another object of my invention is to provide means, whereby the wheel shafts of an amusement coaster may be maintained substantially parallel with the radial lines of the curved track section, so that the tendency for the flanges of the wheels to grind against said curved track may be greatly decreased.

Other objects and applications of my invention, as well as details of construction and operation, whereby my invention may be practiced, will be apparent more fully hereinafter, when taken in connection with the accompanying drawing, wherein

Fig. 1 is a side elevational view of a gravity-operated coaster embodying my invention;

Fig. 2 is a transverse, sectional view taken on the line II—II of Fig. 1;

Fig. 3 is a top plan view of the trucks of Fig. 2, the body being shown in dot-and-dash lines; and

Figs. 4 and 5 are enlarged, detail, inverted plan and side elevational views of one of the wheel-supporting units.

Referring to Fig. 1 of the drawings, a gravity-operated coaster 1 is provided with a plurality of flanged wheels 2 disposed in pairs 3 and 4 that are respectively positioned at the front and rear ends 5 and 6 of the coaster. The wheels 2 may be mounted on a track structure 7 having a curved section 8 in engagement with the front pair of wheels 3 and a straight section 9 in engagement with the rear pair of wheels 4.

The coaster 1 comprises front and rear seats 11 and 12 which are mounted on spaced elongated side beams 13 and 14 respectively, resting on upper edges of a pair of side wall beams 15 and 16 interconnected by a floor 17. A pair of beams 18 and 19 are mounted in spaced relation on one side 21 of the coaster immediately adjacent to the side beam 14 to provide a wheel chamber 22. A

running board 23 is secured on the upper edge of the beams 18 and 19, while a pair of spaced base plates 24 and 25 having central openings 26 through which the wheels 2 may extend are mounted on the lower edge 55 of beams 18 and 19, as shown in Fig. 1.

A similar construction is provided on an opposite side 27 of the coaster, a running board 28 being mounted on a pair of beams 29 and 31 spaced to receive the car wheels 60 2, as illustrated in Fig. 2. A pair of base plates 32, 32 are mounted on a lower edge 65 of the spaced beams 29 and 31, as in the case of the base plates 24 and 25, and they are provided with perforations 33 through 65 which the wheels 2 may extend into the wheel space intermediate the beams 29 and 31.

The wheels 2 of the rear pair of wheels 4 adjacent to the side 21 of the coaster are 70 provided with a shaft 34 that is mounted in bearings 35 and 36 supported in spaced depending side flanges 37 and 38. These flanges constitute integral portions of a bracket member 39 having a central opening 75 41 for the wheels 2 substantially in alignment with the opening 26 in plate 24. An upper side 42 of the bracket member 39 is adapted to engage slidably an adjacent underside 43 of the base plate 24 and it may 80 be supported clamped in this position by end plates 44 and 45, respectively, which are secured by bolts 46 to the underside 43 of said base plate 24.

The rear end plate 45 is preferably provided with a recess 47 adapted to receive a rear end portion 48 of the bracket member 39, as shown in Fig. 5. A lower wall 49 of the recess 47 is clamped in slidable engagement with an adjacent bearing side 51 90 of the end portion 48. An arcuate side wall 52 of the recess 49 is formed complementary to a curved wall 53 of the end portion 48. An enlarged aperture is formed in the end portion 48 for the receipt of a central portion 55 of a king pin 56. Upper and lower end portions 57 and 58 of the pin 56 are of reduced dimensions and disposed in adjacent apertures 59 and 61 respectively formed in the base plate 24 and the end plate 45. Thus, 100

a pivotal mounting is afforded the end portion 48 of the bracket 39, movement being in a substantially horizontal plane transversely of the coaster.

5 The front end plate 44 is similarly provided with a recess 62, forming a supporting or clamping shoulder 63 for a projecting end portion 64 of the bracket member 39. The end portion 64 has a curved wall 65 and 10 the recess 62 a complementary side wall 66. The swinging or pivotal movement of the bracket 39 may be limited by means of a projecting shoulder 67 which extends from the curved side wall 66 of the recess 62 into a 15 recess 68 formed in the adjacent end portion 64 of the bracket 39. The length of the recess 68 is such that the wheels 2 may move to the right or left of their mid position an amount sufficient to permit the flange of the 20 wheel 2 to be maintained tangent to the curvature of the track, all as will appear hereinafter in greater detail. The opposite wheel 2 of the rear pair 4 is similarly mounted on a hinged bracket 69 and positioned in 25 abutting relation to an underside 71 of the base plate 32.

In accordance with my invention, each of the bracket members 39 and 69 are interconnected by a tie bar 72, the opposite ends 30 of which extend through the wall beams 15 and 16 and are pivotally connected by pins 73 and 74 to extensions 75 and 76 from the brackets 39 and 69, respectively. The bar 72 may be positioned substantially in 35 the upper horizontal bearing surface 42 of the bracket members 39 and 69, respectively. Hence, a transverse movement of one of the rear wheels 2 caused by the passage of the coaster over the curved track section 9 is 40 imparted to the other so that the shafts 34 of these wheels are maintained substantially in alignment with the radial lines of the track curvatures. The wheel flanges, therefore, are prevented from grinding against 45 the curved portions of the track structure and a proper relation between the wheels and track structure assumed.

The wheels 2 in the front pair 3 are similarly swingingly supported and interconnected, as shown, for example, in Fig. 3. It is noted, however, that the position of the several parts is reversed, the hinged end 50 of the front brackets 39 being immediately adjacent to the corresponding end of the rear brackets 39. The operating effect of the straight track section 8 on the wheels 2 of the front pair 3 as well as the effect of the curved track section 9 on the rear pair 55 of wheels 4 is shown in Fig. 3.

60 While I have shown only one embodiment of my invention, for the purpose of describing the same and illustrating its principles of construction and operation, it is apparent that various changes and modifications may 65 be made therein, without departing from the

spirit of my invention, and I desire, therefore, that only such limitations shall be imposed thereon as are indicated in the appended claims or as are demanded by the prior art.

70 I claim:

1. Amusement apparatus comprising a curved track, a car body having a pair of wheels movable over said track, means for independently swingingly mounting said 75 car wheels, means including a tie bar, whereby a swinging movement of one wheel may be imparted to the other, and means operatively associated with said first-mentioned means for limiting said swinging 80 movement.

2. A gravity operated amusement system comprising a curved track, a car body, a pair of flanged wheels, means including a pair of brackets, whereby said wheels may 85 be swingingly mounted on said car body, a tie bar secured to said brackets, whereby said flanges may be maintained in a tangential relation to the curvatures of said track as said car body moves over the same, and means independent of said tie bar for limiting the swinging movement of at least one 90 of said brackets.

3. In a gravity-operated coaster system, the combination with a curved track, of a 95 car body, a pair of wheels for said car body having axles, supporting brackets for said axles, means for swingingly mounting said brackets at one end and slidably mounting the same at the other end, and a tie bar 100 connected to said brackets to insure a desired relationship between the wheel axles and the radius of curvature of said track.

4. In an amusement railway system, the combination with a curved track, of a car 105 body, a pair of flanged wheels, shafts for said wheels, supporting brackets for said shafts, means including a pair of end members affording said brackets a hinged mounting at one end and a slidable mounting at the other 110 end, and a tie bar having the ends thereof pivotally mounted on said brackets, respectively, whereby said axles may be maintained in the radial lines of said curved track as said car body traverses the same. 115

5. A coaster comprising a car body, a car wheel, a supporting bracket for said wheel, and means including a pair of spaced clamping members, affording one end of said bracket a hinged mounting and the other 120 end a guiding surface.

6. A coaster comprising a car body, a car wheel, a supporting bracket for said car wheel, means affording said bracket a pivotal mounting at one end and a slidable mounting at the other end, and means for limiting the pivotal movement of said bracket. 125

7. An amusement car having a wheel, a bracket for supporting said wheel, a base 130

member, and means whereby said bracket may be positioned in operative relation to said base member, said means comprising a pair of members recessed to receive the end 5 portions of said bracket and means for securing said members in operative relation to said bracket end portions and said base member.

8. In an amusement system, the combination with a curved track, of a coaster, a pair of supporting wheels for said coaster, each of said wheels having a bracket, means affording said bracket a limited swinging movement, and means whereby the swinging 15 movement of one wheel may be imparted to the other.

9. In an amusement system, the combination with a curved track, of a coaster and a pair of supporting wheels for said coaster, 20 each of said wheels having a bracket, a base section and a pair of clamping members for securing said bracket in sliding relation to said base section.

10. A wheel, a supporting bracket there- 25 for having an upper bearing surface adapted to engage slidably a base member and a pair of supporting end plates operatively associated with the ends of said bracket, means associated with one of said end plates,

whereby said bracket may be pivotally 30 mounted, and means associated with the opposite end of said bracket for limiting the pivotal movement thereof.

11. A base plate, a wheel-supporting bracket and means for mounting said bracket in slidable engagement with said base plate comprising a pair of end plates recessed to receive ends of said bracket and a removably clamped to said base plate and a pivot pin operatively associated with said bracket and one of said end plates, the other of said end plates having a projecting shoulder and the co-operating end of said bracket member having a recess for said shoulder, whereby said bracket may have a limited 45 movement only.

12. The combination with a wheel-supporting bracket member, of a base structure, and means for mounting said bracket member in operative relation to said base structure, said means comprising a pair of end members recessed to receive end portions of said bracket member, said bracket member and one of said end members having co-acting portions adapted to limit the movement 55 of said bracket member.

HERBERT P. SCHMECK.
